UNITED STATES PATENT OFFICE.

HAROLD G. WARR, OF CHICAGO, ILLINOIS, ASSIGNOR TO THE P. & M. CO., OF CHICAGO,
ILLINOIS, A CORPORATION OF ILLINOIS.

ANTICREEPER.

1,260,608.

Specification of Letters Patent. Patented Mar. 26, 1918.

Application filed June 18, 1918. Serial No. 103,962.

To all whom it may concern:

Be it known that I, HAROLD G. WARR, a citizen of the United States, residing at Chicago, in the county of Cook and State of Illinois, have invented a certain new and useful Improvement in Anticreepers, of which the following is a full, clear, concise, and exact description.

My invention relates to anti-creepers or rail anchors more particularly of the type wherein a transverse member is held to one side of the rail base by a jaw thereon which fits over said base and is held at the other end by a clip or dog in the general form of a jaw which fits beneath the transverse member and over the side of the rail base to hold said member up against the bottom of the rail base.

Anti-creepers constructed along such lines, when put in service have, in many cases, proved unsatisfactory due to the stretching or slight elongation of the dog or lock as it is being forced into position. The result of such elongation is that the end of the anchor engaged by said dog is not held to the rail base as firmly as might be desired, thereby diminishing the effectiveness of the anti-creeper as a whole.

The object of the present invention is to provide an improved anti-creeper in which this objection is overcome. Two embodiments of the invention are shown in the accompanying drawings in which said object is attained by a resilient structure which yieldingly engages the rail base, whereby when the parts are forced into position, the transverse member yields somewhat instead of the dog, the effectiveness of the anchor as a whole being unimpaired by said yielding action. Said object may be attained by other structures however, which fall within the scope of the invention.

Figure 1 of the drawings is a rear elevation of the rail anchor, a portion of the rail being shown in section.

Fig. 2 is a top plan view of the base of the rail with the rail anchor thereon.

Fig. 3 is a rear elevation of a rail anchor showing the relative position of the parts as the anchor is being applied to the rail base.

Fig. 4 is a perspective view of the clip or dog.

Fig. 5 is a perspective view of the transverse member.

Fig. 6 shows the blank from which the rail anchor is formed, and Fig. 7 is a modification.

The rail anchor in the first form illustrated, is of two part construction consisting of a transverse member 1 made preferably of spring steel and a clip or dog 2 also stamped from a steel plate. The blank from which the transverse member is made is shown in Fig. 6. One end is bent around to form a jaw 3 having an offset extension 4 whereby a shoulder 5 is formed. The lateral projection is bent down to form a tie-abutting flange 6 having an extension 7 thereon, which is bent at right angles to 70 form a reinforcing flange which is arranged to bear upwardly against the main body of said transverse member. The other end of said member is bent to form a downward extension 9 which is provided with a notch 10, which notch is adapted to receive the dog 2. Said dog is notched out to form what is in effect a jaw. The upper surface 11 of said jaw is arranged to bear against the upper side of the rail base. The lower surface thereof is preferably provided with a notch 12 arranged to fit within the notch 10 in the transverse member. The vertical wall 13 of said jaw is arranged to contact with the vertical edge of the rail base.

To assemble the device on the rail, the transverse member 1 is placed thereon in approximately the position shown in Fig. 3 with the rail flange projecting as far as possible into the opening in the jaw 3. In this position, the downward extension 9 projects beyond the other side of the rail base. The transverse member 1 is curved or crowned somewhat being in contact with the base of the rail for only a portion of its length, as shown in Fig. 3, thereby providing a clearance between itself and the rail base near the opposite sides of the latter. In this position the dog 2 may be hooked under the extension 9 and fitted over the top of the base flange as shown in said Fig. 3. The dog and the transverse member are then forced to the left either by hammering them or applying force in any suitable manner. During such movement the inclined surface 11 of the dog rides upwardly along the inclined top of the rail base, thereby raising the notched portion 12 and also the downward extension 9 of the transverse member which is engaged therewith. Simultaneously, the

jaw 3 moves away from the opposite side of the rail base. The movement of the device as a whole to the left puts the transverse member 1 under increasing tension as said movement continues. By the time the vertical wall 13 of the dog comes in contact with the adjacent vertical wall of the rail base, the member 1 is under considerable tension, and simultaneously the shoulder 5 slips over the opposite edge of the rail base permitting the extension 4 to snap downwardly against the top of the rail base, said shoulder 5 locking the parts against return movement. In this position it will be seen that the anchor is locked against movement in either direction. The right hand end of the transverse member is firmly clamped against the rail base by the dog 2, and the left hand end thereof is held in firm frictional engagement with the top 20 of the rail base due to the downward pressure of the extension 4 thereon. The rail anchor is so positioned that its downwardly extending flange 6 bears against the cross tie 14 in the usual manner, thereby transmitting thereto the creeping thrust of the rail 15 which is supported on said tie.

The creeping of the rail is checked by the rail anchor but the initial movement of the rail may tilt the dog 2 somewhat out of a vertical plane. However, such tilting action serves only to further increase the grip of the rail anchor on the rail base. It will be seen that the grip is thus increased upon tilting of said dog in either direction, reverse tilting being effected if the rail moves rearwardly, due to its contraction or reversal of traffic, in which case rearward movement of the anti-creeper is resisted by the ballast in which the flange 6 is embedded. Such rearward movement is resisted more particularly in winter when the ballast may be frozen into a solid mass.

If it becomes necessary to remove the rail anchor, such removal may be effected by forcing up the left hand end of the transverse member 1 and driving said member to the right to return the parts to the position shown in Fig. 3, whereupon the dog and transverse member may be separated from each other and both parts readily removed from the rail.

The anti-creeper shown in Fig. 7 is similar in most respects to the one previously described. It consists of a transverse member 14' having a jaw 15' which fits over one side of the rail base, the downwardly extending projection 16 at the other end having a notch which cooperates with the dog 17. The latter has a notch 18 which cooperates with the notch in the downward projection 16, and has an inclined surface 19 which guides the latter as hereinafter explained. The rail base fits within a notch or recess 20 whereby the rail is gripped both above and below and any tilting action results in increasing

the grip. The dog is first applied to the rail and held against movement by a bar 21 for example, after which the transverse member is driven into position by a maul 22. The downward extension 16 rides along 70 the inclined surface 19 until the notch therein snaps into the notch 18, whereupon the parts are locked against movement.

It is apparent that the type of dog described with the second form of device may 75 be used with the first form of device if desired, and vice-versa. In general the invention is not limited to the embodiments thereof illustrated in the accompanying drawings, as other forms may be devised which fall 80 within the scope of the claims.

Having thus described my invention, what I desire to secure by Letters Patent of the United States is:

1. A rail anchor comprising a transverse 85 member normally curved downwardly at opposite ends, a jaw integral with one end thereof, and a dog arranged to draw said other end upwardly against the rail base when said member is moved transversely 90 thereof to position the parts thereon.

2. A rail anchor comprising a transverse member beneath the rail base, means at one end thereof for holding said end to the rail, means at the other end thereof for holding 95 said other end to the rail, said other end normally tending to spring away from the rail base whereby it is maintained under tension by said second means, the positioning of said second means being effected by 100 lateral movement of said transverse member across the rail base, and means associated with said first means for preventing return movement.

3. A rail anchor comprising a transverse 105 member having a jaw at one end, and a dog for holding the other end of said member to the rail base, said dog being applied to the latter when the opposite side of the rail base is received well within said jaw, the 110 final positioning of said parts providing a clearance between the vertical wall of said jaw and the adjacent edge of the rail base.

4. A rail anchor comprising a transverse member having a jaw at one end, a dog for 115 holding the other end of said member to the rail base, said dog being applied to the latter when the opposite side of the rail base is received well within said jaw, the final 120 positioning of said parts providing a clearance between the vertical wall of said jaw and the adjacent edge of the rail base, and means for maintaining said parts in said latter position.

5. A rail anchor comprising a transverse 125 member curved downwardly at opposite ends, a jaw integral with one end thereof, a clip arranged to force said other end upwardly against the rail base when said member is moved transversely with respect to 130

the rail, and a shoulder on the upper side of said jaw which snaps downwardly against the edge of the rail base to maintain the parts in final position.

- 5 6. A rail anchor comprising a transverse member having a jaw at one end, the upper portion of said jaw having an offset extension, a tie-abutting flange at an intermediate portion of said member, and a downward extension at the other end thereof, a clip engaging said downward extension and one side of the rail base, the other side of said rail base being engaged by said offset extension.
- 10 7. A rail anchor comprising a clip having an inclined surface to engage the inclined surface of the rail base near one edge thereof, and also having a horizontal surface, and a vertical surface, a transverse member one end of which has positive engagement with said horizontal surface, the other end of said member being curved around to fit over the other opposite inclined side of said rail base, thereby forming a jaw, there being a clearance between said jaw and the adjacent edge of the rail base when the vertical edge of said clip is in engagement with the adjacent side of the rail base, said transverse member being under tension, whereby said jaw bears downwardly against the top of the rail base.

- 15 8. A rail anchor consisting of a transverse member having one end doubled back to form a jaw, the end of said jaw being offset whereby a shoulder is provided, an integral

downward extension on said member forming a tie-abutting flange and having a portion bent rearwardly to form a brace, the other end of said member being bent downwardly and having a notch in its lower extremity, a clip in the form of a jaw having a notch in the lower wall thereof fitting said first notch and having an upper wall engaging said upper side of the rail base, said transverse member being maintained under tension by said jaw and clip.

40 9. A blank for a rail anchor consisting of a strip of spring steel having an intermediate projection from which a tie-abutting flange is formed, said projection having a lateral extension from which a brace is formed, said strip being notched at one end.

45 10. A blank for a rail anchor consisting of a strip of spring steel having an intermediate projection from which a tie-abutting flange is formed, said projection having a lateral extension from which a brace is formed.

50 11. A rail anchor comprising a transverse member normally curved downwardly at opposite ends, a jaw integral with one end thereof, a dog arranged to draw said other end upwardly against the rail base when said member is moved transversely thereof to position the parts thereon, and means to maintain said parts in position.

55 In witness whereof, I hereunto subscribe my name this 6th day of June A. D., 1916.

HAROLD G. WARR.

Correction in Letters Patent No. 1,260,608.

It is hereby certified that in Letters Patent No. 1,260,608, granted March 26, 1918, upon the application of Harold G. Warr, of Chicago, Illinois, for an improvement in "Anticreepers," an error appears in the printed specification requiring correction as follows: Page 3, line 9, claim 6, for the word "down" read *downward*; and that the said Letters Patent should be read with this correction therein that the same may conform to the record of the case in the Patent Office.

Signed and sealed this 30th day of April, A. D., 1918.

[SEAL.]

Cl. 238--4.

F. W. H. CLAY,

Acting Commissioner of Patents.
